UNITED STATES PATENT OFFICE

BERNARD J. WEKENBORG, OF ARGYLE, MISSOURI

COMBINED STARTER AND CHOKE CONTROL

Application filed January 15, 1932. Serial No. 586,807.

This invention appertains to new and useful improvements in control devices for automobiles and more particularly to a novel control whereby the starter switch and engine choke can be actuated simultaneously by a single control.

Other important objects and advantages of the invention will become apparent to the reader of the following specification.

10 In the drawings:—

Figure 1 represents a fragmentary front elevational view disclosing the control connections.

15 Fig. 2 represents a fragmentary top plan view of the operating rod and connection to the starter switch.

Fig. 3 represents a sectional view taken substantially on line 3—3 of Fig. 2.

20 Fig. 4 represents a fragmentary side elevational view of the invention.

Fig. 5 represents a fragmentary side elevational view showing the flexible connection supported by the fuel pipe.

25 Referring to the drawings wherein like numerals designate like parts, it can be seen that numeral 5 designates the usual internal combustion engine, with the fuel supply line at numeral 6 and the choke control at numeral 7.

30 Numeral 8 represents the usual steering column housing to which is secured one or more brackets 9 each having a bearing 10 through which the control rod 11 is both slidably and rotatably disposed. The upper 35 end of this rod 11 is provided with a lateral handle 12, while its lower end is provided with threads 13. This rod 11 is disposed through an opening in the angle bracket 14 and jamb nuts on opposite sides of the bar numbered 15, and on the said rods 11 serve to permit the rod to rotate in the opening of the bar 14, but permits the rod to rock the angle bar 16, due to the fact that the bracket 14 is secured to the angle bar 16 as at 17 and 40 at one side of the fulcrum pin 18, the bar 16 being fulcrumed on the U-strap 19 which is secured to the steering shaft housing 8 in a suitable manner.

45 Numeral 20 represents the rod connected to the contactor of the starter switch and is

equipped with a foot engageable button 21 at its upper end. This rod 20 is also equipped with a collar 22 over which the fork formation 23 on the end of the bar 16 opposite from the bracket 14 engages.

55

A lever 24 is secured to an intermediate portion of the control rod 11 and from this extends the flexible wire or cable 25.

50 A flexible conduit 26 is secured by clamps 27 to the engine 5 and by clamps 28 to the fuel pipe 6 and extending through this conduit 26 is the control wire 25 which connects to the choke control 27 as shown in Fig. 1.

55 It can now be seen, that by pulling upwardly on the rod 11, the starter switch will be closed, and simultaneously by rotating the rod 11, a pull will be exerted on the cable 25 to properly regulate the choke 7.

60 While the foregoing specification sets forth the invention in specific terms, it is to be understood that numerous changes in the shape, size and materials may be resorted to without departing from the spirit and scope of the invention as claimed hereinafter.

65 Having thus described my invention, what I claim as new is:—

70 In combination, a throttle, a steering shaft housing, a bearing on the housing, a swingable member on the housing, an elongated rod extending through the bearing, a swivelled connection between one end of the rod and the swingable member, a lever on the rod, a connection between the lever and the throttle, an engine starter control member having a shoulder thereon, one end of the swingable member being equipped with a yoke for receiving the starter control member and to engage the shoulder, and a handle on the 75 forementioned rod whereby the rod can be rotated or slid through the said bearing to oscillate the lever on the rod or to rock the said swingable member for controlling the 80 starter.

85 BERNARD J. WEKENBORG.
